UNITED STATES PATENT OFFICE.

FRANCIS W. HALE, OF BOSTON, MASSACHUSETTS.

PIANO-FORTE.

SPECIFICATION forming part of Letters Patent No. 396,155, dated January 15, 1889.

Application filed May 7, 1888. Serial No. 273,100. (No model.)

To all whom it may concern:

Be it known that I, FRANCIS W. HALE, of Boston, in the county of Suffolk and State of Massachusetts, have invented a new and useful Improvement in Piano-Fortes, of which the following, taken in connection with the accompanying drawings, is a specification.

The object of my invention is to so improve that class of piano-fortes with which a "click" or dummy action is combined that by a single motion of a lever all of the hammers may be pressed forward to the strings and all of the stickers be raised upward out of the action of the keys; also, in case the stickers are attached to the keys, as they are in some cases, then the jacks may be thrown out of working action; also, in combining with the keys a series of levers adapted to hold the keys up and arranged to be adjusted so as to resist any desired degree of pressure on the keys; also, to connect with the keys a device by which an electric sounder may be operated to indicate the exact character and relative time of the player's practice; also, in several minor details, which may be best understood by reference to the specification and drawings. These objects I attain by the mechanism shown in the accompanying drawings, in which—

Figure 1 is an end elevation (casing being removed) showing the working parts or "action." Fig. 2 is an end elevation showing all that part of the action above the keys more in detail, some parts being omitted to prevent confusion in the drawing. Fig. 3 is an enlarged view showing the mechanism (located beneath the keys) by which an adjustable resilience or resistance to pressure is given to the keys, and also showing in end section the electric click device. Fig. 4 shows in elevation parts relating to the adjustable resilience device. Fig. 5 shows in perspective the electric click arrangement and a diagram illustrating the switch-connections with the battery and sounder, and Fig. 6 is an enlarged elevation of details.

As most of the action above the keys is of ordinary construction, but a brief description may be given.

In the drawings, Fig. 1, A represents the key-board of the piano-forte, A' one of the

keys, and A² the pin upon which the key oscillates; and A³, Figs. 1 and 2, represents one of the stickers.

Now, referring to Fig. 2, E E² is a bracket, 55 of which there are two, one at each end of the piano-forte. These brackets are connected together by rails A⁵, B⁵, and C⁵, and together with said rails form a frame to which the action is connected. The brackets E are connected at their lower end to the body of the piano by a pin, E', and at their upper ends by bolts E³ with the sounding-board F.

The sticker A³ is not attached directly to the key, but simply rests upon it, and is held 65 in place by a link, A⁴, said link A⁴ being pivoted at a to the sticker and at a' to the extension or sticker rail A⁵. The upper end of the sticker A³ is attached to the lever B by a pivot, a², the lever B being attached by a pivot, 70 b', to a bracket, B⁶, extending downward from the flange-rail B⁵. On the lever B a small projection, B', is attached, which serves to support the lower end of the jack B², the said jack B² being pivoted to it at b. 75

B³ is a small spring under the toe of the jack B², which serves to throw the upper end of the jack B² under the shoulder of the hammer-piece C. The hammer C C' C² is pivoted at c, and is provided with a check or 80 back-stop, C⁴, which in the rebound comes in contact with the stop B⁹, attached by a stem, B⁸, to the lever B.

B⁴ is a stop attached by an arm to the flange-rail B⁵, and serves by checking the upward 85 action of the toe of the jack B² to throw the upper end of the said jack out from under the shoulder of the hammer-piece C, and thus allow the hammer to drop back. This action takes place while the lever B is as- 90 cending—that is, while the key is being depressed; but when the lever B descends the toe, no longer controlled by the stop B⁴, is thrown upward into place and the upper end of the jack back to its resting position under 95 the shoulder of the hammer-piece C.

The damper device consists of a lever, D', pivoted at d to a projection, B⁷, attached to the flange-rail B⁵. This lever D' has at its upper end a stem, D³, to the upper end of 100 which the damper D⁴ is attached.

D² is a spring attached to the flange-rail B⁵,

which serves to throw the damper D^4 onto the wire, unless the same is forced away by the movement of the lever B .

The device for throwing the damper away from the string consists of an upright, D , usually called a "spoon," attached to the lever B behind the pivot b' , so that the upward movement of the forward part of the lever B , which, as has been explained, causes the hammer to dart forward to strike the wire, will at the same time, acting through the spoon D , throw the lower end of the lever D' backward, thus causing the upper end of the said lever to move forward and withdraw the damper D^4 from the wire.

When it is desirable to throw the hammers out of action, so that the pupil may practice on the keys with the click attachment, the following device is used, (see Figs. 1 and 5:)

G is a lever pivoted at G' , its rear end passing under the forward end of the lever B . To the front end of the lever G , I have a rod, G^3 , which serves to connect the said lever G with a hand-lever, G^7 . (See Fig. 1.) This hand-lever G^7 is pivoted at G^8 and has a swinging handle, G^9 , pivoted to it at g' . This swinging handle is so formed that when in use it can be turned up so as to become parallel with the lever G^7 , a shoulder preventing it from going any higher unless the lever G^7 moves with it. By moving up the forward end of the lever G^7 by means of the handle G^9 the rear end is depressed, and, acting through the rod G^3 , the forward end of the lever G is drawn down, thus throwing up the rear end, G^2 , (see Fig. 2,) causing the levers B to be raised up so as to withdraw the stickers A^3 from the action of the keys. At the same time that this action is taking place the bent lever G^5 G^6 (see Fig. 6) is thrown forward by the cam-like action of the end G^2 of the lever G upon the part G^5 , thus causing the upper end of the lever G^5 G^6 to move against the hammer-stem rail C^3 , (see Figs. 1 and 2,) and, forcing it backward, causes it to throw all of the hammers back onto the wires and there hold them.

In some pianos the stickers are attached to the keys and it is not practical to lift the lever B by the lever G , as has been described. In this case I place a rod, B^{10} , Fig. 2, immediately behind the jacks B^2 . This rod B^{10} is connected to a lever, (not shown,) by which it may be drawn forward against the jacks, and thus throw their upper ends out from under the shoulder of the hammer-piece C , so that, although the keys may be played upon, the hammers will not be moved.

The device by which an adjustable resilience or resistance to pressure is given to the keys is shown in Fig. 3, and may be described as follows:

H , Figs. 1 and 3, represents a metallic plate, of which there are two, one at each end of the piano. These end plates, H , are securely attached to each other by means of the longitudinal strips H' H^2 and the rail H^3 . Upon

the rail H^3 , I have two sets of standards, H^4 H^6 , adapted to hold the regulating-levers L . The pivot at one of these levers is shown at L' , 70 and there are as many of these levers as there are keys on the instrument. Levers L , that are used for the sharps, are pivoted upon the standard H^4 , while the levers for the white keys are pivoted upon the standard H^6 . Each 75 lever L is connected to its respective key by a sticker like L^2 , Figs. 1 and 3. To the rear end of the lever L , I attach a link, L^4 , by means of a pivot, L^5 . The lower end of the link L^4 is attached by a pivot L^5 to a lever, L^6 , which 80 swings on a pivot, M^4 , in the standard M^3 .

L^7 is a cord, which serves to connect the upper end of the lever L^6 with the spring L^8 . This cord may be of linen or any other flexible material. The standards M^3 are all attached to a rail, M^2 , said rail M^2 being affixed at each end to segment-gears M^M . Said segment-gears M^M swing on pivots, as indicated at M' , and are operated by pinions M^5 , attached to a central shaft, M^6 , said shaft M^6 90 extending from one end of the piano to the other. In Fig. 1 I have shown a device for swinging these segments. This device consists of a hand-wheel, M^9 , shaft M^8 , and worm M^7 , said worm M^7 operating upon one of the 95 pinions M^5 , and through its shaft M^6 to the corresponding pinion at the other end of the piano.

From the above description it will be seen that as the key descends it, acting through the sticker L^2 , will cause the outer end of the lever L to ascend; but this ascent is resisted by the action of the spring L^8 . Thus if the forward end of the lever L descends its rear end must be elevated, and, acting through the link L^4 , raise the lower end of the lever L^6 , and thus throwing the upper end of the lever L^6 back, so as to strain on the spring L^8 . In fact, the resilience exerted by the lever L is in proportion to the tension on the spring L^8 , so that if the gear-segment M is thrown backward it will carry the levers L^6 , and, increasing the tension of the spring L^8 , will increase the resilience of the lever L ; but if the segments M and all their parts are swung forward, then the tension on the spring L^8 will be decreased, and the resilience of the lever L will consequently be decreased. Thus by simple movement of the segment-pieces M and their connecting parts (by means of the hand-wheel M^9 , Fig. 1, as has already been described) any degree of resilience may be given to the lever L .

An important advantage is gained by arranging the resilient device as above required, viz: The force required to press the key down diminishes as the key descends. This fact will become evident by comparing the position of the lever L^6 , cord L^7 , and spring L^8 as they appear in full line, Fig. 3, (that is, in the position they occupy when the key is not depressed,) with the position the same parts occupy (indicated by dotted lines) when the key is depressed, in which it will be seen that

the spring L^8 , acting through the cord L^7 , acts much more directly and with more force to pull the upper end of the lever L^6 forward when the key is not depressed, as indicated 5 by the full lines, than it can act when the lever L^6 is in the position indicated by the dotted lines. To illustrate, if we imagine the lever L^6 so turned as to become parallel to the cord L^7 , then the power of the spring L^8 will 10 be completely counteracted or nullified, while if the lever L^6 should assume a position at right angles to the cord L^7 then the spring L^8 would have its full efficiency.

A point of special mention is found in the 15 position and motion of the rail M^2 as related to the lever L , the link L^4 , and the spring L^8 , as I will now explain. When the rail M^2 is brought forward in the direction of the spring L^8 , the amount of force required to operate the 20 lever L is at its minimum for two reasons—viz., the spring has but little tension and the position of the short lever L^6 is as shown in Fig. 4. This causes the draft of the spring through the cord L^7 to lie nearer in line with 25 the lever, and consequently is of diminished power. If, however, the rail M^2 is moved away from the spring L^8 , it not only increases the tension of the spring through the cord L^7 , but as the lever assumes the position of the heavy 30 lines shown in Fig. 3 the power of the spring is made doubly effective. By means of this combination I can use a much lighter spring, and not only save expense and avoid the injurious results of a series of very stiff springs, 35 but produce a more even and satisfactory “touch.”

The resisting-bar L^9 is for the purpose of 40 retarding the upward motion of the key, so as to avoid the thumping sound produced by the lever L striking when it comes back to its point of rest. When the spring L^8 is drawn forward, the lever L^9 is drawn down behind the spring L^8 by its own spring L^{11} , as shown in dotted lines of Fig. 3. If at this point the 45 finger is instantly taken from the key above, the spring L^8 is unable to overcome the resistance of the spring L^{11} through the lever L^9 rapidly enough to cause the lever L to thump when it reaches its point of rest. The shape 50 of the spring L^8 and the lever L^9 effectually prevent the lever L^9 from clogging. The rocker L^{10} serves the purpose of regulating the lever L^9 .

Before describing that part of my invention 55 which relates to the click device I will briefly explain its use.

In piano technique two things are of special importance—viz., in scales and arpeggios a perfect legato and in chords a simultaneous 60 action of every finger—*i. e.*, key. I accomplish the former (*i. e.*, legato) by use of an open-circuit electrical connection, as illustrated in Fig. 5. If a perfect legato is being performed, there will be no click from the 65 sounder after the first, since one finger does not leave the key—*i. e.*, break the circuit—until the next has taken its place. In regu-

lating the point at which the circuit shall be “made” I prefer to do so very near the bottom of the “dip” of the key as it descends, 70 and the same to be broken at the same point as the key ascends, although it may be regulated at any point of the key’s dip.

I accomplish the click for irregular chord or octave technique by means of a closed circuit, as shown in Fig. 5, instead of an open circuit, as I believe the action of the magnet is more rapid and positive in this case and a more perfect result is obtained. I can, however, use an open circuit for this purpose as 80 well as for the legato touch. If the notes of a chord are not struck simultaneously, the circuit will be broken and made by each key and a corresponding click from the sounder will be given for each; but if the keys are all 85 struck simultaneously one click only will be heard in the descending action and one in the ascending action. I mute either the downward or the upward contact of the sounder, usually the former, which prevents a double 90 click for one motion of the key—that is, one when the circuit is broken and one when it is made—as explained in connection with Fig. 4.

The click device used in this instrument is shown in Figs. 3 and 4, and may be described 95 as follows: A click-rail, P , Fig. 3, extends from one end of the piano to the other and has upon it as many click devices as there are keys, which are operated by the respective levers L , each lever L having a click-striker, L^{14} . 100 The clicks themselves each consists of a spring-plate, $P' P^2 P^3 P^4$, which is attached by a screw, S , to the click-rail R . The prongs $P^1 P^2$ of the spring-plate P' are about one-sixteenth of an 105 inch apart. Each, also, has a contact-hook of metal, $P^5 P^6$, and a contact-spring, R . (See Figs. 3 and 5.) The contact-springs are each attached to a strip, R^2 , of metal. (See Figs. 3 and 5.) As has already been stated, I arrange my electric connections for using either a 110 closed or an open circuit. The closed circuit consists of the following system: Starting from the zinc of the battery, the line passes through Z^6 to the sounder T , thence through the line Z^3 , switch-point Z^4 , line $Z^3 Z^4 Z^8$ to the spring-plate P' of the last click, from thence to the 115 contact-hook $P^6 P^5$, thence through Z^9 to the spring-plate of next to the last click, thence to the corresponding contact-hook, and so on through all of the clicks until it reaches the 120 first one. Thence the current takes the line Z and Z' to the switch-point Z^{10} . Now the current passes through the end S of the switch, the said switch being in the position indicated by the dotted lines, thence through the metal 125 plate S^3 , and the line $K^2 K^3$ to the carbon of the battery. When the lines are thus arranged, it will be seen that the circuit is closed and the sounder held down so long as the part P^2 of the spring-plate P' touches the contact-hook $P^5 P^6$; but if the said circuit is broken 130 by the downward action of the key a click will be heard. This circuit stays broken until the part P^1 of the spring-plate P' is suffi-

ciently depressed to bring it down upon the contact-hook $P^5 P^6$, which recloses the circuit; but I mute the sounder, so that there shall be but one click for a single motion of the key. The upward motion of the key produces the same conditions and corresponding click as the downward motion just explained. It will now be seen that if one key descends in advance of another sufficiently to allow it 10 to open and close the circuit before the other reaches the spring-plate P' there will be two distinct clicks before both keys have reached the bottom of their dip, while if both reach the spring-plate P' at the same instant but 15 one click will be made, as should also occur from any number of keys when struck simultaneously.

To use my legato click device on an open circuit the arrangement is as follows: The 20 switch is placed in position indicated by full lines, in which case the current goes from the zinc through the line Z^6 , sounder T, line $Z^7 Z^8$ $Z^7 Z^8$, spring-plates P' of the last click, thence to the contact-hook $P^6 P^5$, thence 25 through Z^9 to the spring-plate of the next to the last click, thence to the corresponding contact-hook, and so on through all of the clicks until it reaches the first one. Thence the current takes the line Z to the switch-point Z^{10} . Thence it 30 couples through the part S^2 of the switch back to the zinc of the battery through the line Z^3 $Z^4 Z^5$, &c. Thus it will be seen that I have a double line from the zinc of the battery extending from the switch-point Z^4 entirely 35 through the click. The carbon line starts from the carbon through K^3 and K^2 to the plates S^3 , thence through the part S of the switch to the switch-point K' , thence through K to the metal strip R^2 , to which all of the 40 click-springs are attached.

From the above description it will be seen that no circuit is made unless some one of the spring-plates P' be so depressed as to bring it in contact with the corresponding click-spring R . This closes the circuit, and, bringing down the sounder, gives the required click, which will be repeated as soon as the click-plate P' is released. The sounder is not muted as in the closed circuit.

If under the conditions above described a key be made to descend until the spring-plate P' comes in contact with the click-spring R , the circuit will be closed and a single click heard, and so long as the circuit is kept 55 closed by the first key no other key is able to produce a second click.

The contact of the spring-plate P' with the click-spring R is made after the key has spent two-thirds of its dip, and which is 60 usually from one-sixteenth to one-eighth of an inch from the bottom of the dip. The click-spring is carried down by the key after the contact has been made until the key reaches the bottom of the dip, thus keeping 65 the circuit closed until the key has returned to its point of contact. It will now be seen

that in order to operate the keys so that no click shall be heard after the first one the performer must bring each successive key down to the point of contact on or before the 70 previous key has returned to that point. If this is done, a perfect legato touch is attained.

I also make use of the open legato circuit alone—*i.e.*, without combining with the closed 75 circuit, as above explained. When used alone, the spring-plates P' , Fig. 3, would be attached to a metal strip, (not shown,) but in the same manner as are the click-springs R . This metal strip would be continuous with the zinc line 80 of the battery, and the metal strip to which the click-springs are attached being continuous with carbon line of the battery. If now the spring-plate and click-spring are brought into contact, the circuit is closed and a single 85 click heard, which is repeated when the circuit is broken.

In order that the resisting-bars L^9 , Fig. 4, shall only retard the backward motion of the spring L^8 when there is sufficient tension to 90 cause the lever L , Fig. 3, to "thump," I have devised the following mechanism:

L^{14} , Figs. 3 and 4, is a continuous shaft, which is held in position and rotates in the brackets Fig. 1, attached to the plates H , 95 Fig. 1.

L^{18} , Fig. 4, is an arm welded to the shaft L^{14} .

L^{20} is a small rod running under all of the resisting-bars L^9 and attached to the arms L^{18} and extending parallel with L^{14} . 100

The shaft L^{14} has firmly attached to it at each end a crank-arm, L^{15} , the upper ends of which are attached by a pivot at L^{21} to the link L^{16} , said link L^{16} being attached by a pivot at L^{19} to the segment M . (See Fig. 4.) 105 If now the segments M are rotated forward, (reducing the tension on the spring L^8) the link L^{16} will, acting through the crank-arm L^{15} , cause the shaft L^{14} to rotate, and thus (acting through the arms L^{18}) throw up the 110 rod L^{20} , which will lift all of the resisting-bars L^9 upward out of the way of the springs L^8 , as shown in Fig. 4. The lifting of the resisting-bars L^9 takes place only when the forward movement of the segments M have brought 115 the lever L^6 so far forward as to greatly lessen the tension of the spring L^8 —so much, in fact, that it (the spring) will no longer have sufficient force to cause the lever L to thump. This allows the keys to have the least possible 120 resistance—that is, just enough to bring them back to place.

I claim—

1. In a piano-forte, the combination of the hand-lever $G^9 G^7$, rod G^3 , and lever G , having 125 an extension, G^2 , adapted to lift the levers B and to throw forward the upper end of the lever $G^5 G^6$, with the hammer-stem rail C^3 , substantially as described, and for the purpose set forth.

2. In a piano-forte, the combination of the key A' , sticker L^2 , and lever L , with the link 130

L^4 , lever L^6 , cord L^7 , and spring L^8 , all operating together substantially as described, and for the purpose set forth.

3. In a piano-forte, the combination of the key A' , sticker L^2 , lever L , link L^4 , lever L^6 , cord L^7 , and spring L^8 , with swinging segment mechanism $M M^2 M^3$, all operating together substantially as described, and for the purpose set forth.

10 4. In a piano-forte, the combination of the lever L , link L^4 , lever L^6 , cord L^7 , and spring L^8 , with the resisting-bar L^9 , spring L^{11} , and rocker L^{10} , substantially as described, and for the purpose set forth.

15 5. In a piano-forte, the combination of the segment M , link L^{16} , crank-arm L^{15} , shaft L^{14} , arm L^{10} , and rod L^{20} , with the resisting-bars L^9 , all operating together substantially as described, and for the purpose set forth.

20 6. In a piano-forte, the combination of the key A' , sticker L^2 , lever L , and click-striker L^{14} , with the spring-plate $P' P^2 P^3 P^4$ and the contact-hook $P^5 P^6$, adapted to make and

break an electric circuit, substantially as described, and for the purpose set forth.

25 7. In a piano-forte, the combination of the click-striker L^{14} and spring-plate $P' P^2 P^3 P^4$ with the contact-hook $P^5 P^6$, adapted to make and break an electric circuit, substantially as described, and for the purpose set forth.

30 8. In a piano-forte, the combination of the key A' , sticker L^2 , lever L , and click-striker L^{14} , with the spring-plate $P' P^2 P^3 P^4$ and spring-brace R , adapted to make and break an electric circuit, substantially as described, 35 and for the purpose set forth.

35 9. In a piano-forte, the combination of the click-striker L^{14} with the spring-plate $P' P^2 P^3 P^4$ and spring-brace R , adapted to make and break an electric circuit, substantially as described, 40 and for the purpose set forth.

FRANCIS W. HALE.
